(57) **CLAIM**

The ornamental design for an interconnector for joining together freight containers end to end, as shown and described.

DESCRIPTION

FIG. 1 is a plan view of the interconnector;

FIG. 2 is an under plan view of the interconnector;

FIG. 3 is a view from one side of the interconnector;

FIG. 4 is a side view from the opposite side of the interconnector; and,

FIG. 5 is an end view of the interconnector.
